UNITED STATES PATENT OFFICE.

THOMAS J. JOHNSON, OF NORMAN, OKLAHOMA TERRITORY.

WEATHER-STRIP.

No. 831,872.

Specification of Letters Patent.

Patented Sept. 25, 1906.

Application filed February 26, 1906. Serial No. 302,992.

To all whom it may concern:

Be it known that I, THOMAS J. JOHNSON, a citizen of the United States, and a resident of Norman, in the county of Cleveland and Territory of Oklahoma, have invented a new and Improved Weather-Strip, of which the following is a specification.

My invention is an improvement in that class of weather-strips which are hinged to the door and are thrown down when the door is closed by reason of contact with a lateral projection on the door-jamb.

The details of construction, arrangement, and operation of parts are as hereinafter set forth, and illustrated in the accompanying drawings, in which—

Figure 1 is a front view showing my improved weather-strip as applied to a door. Fig. 2 is a vertical cross-section on the line 2-2 of Fig. 1. Fig. 3 is a bottom plan view of the door and weather-strip, a portion of the latter being broken away to show the arrangement of the spring bearing thereon. Figs. 4 and 5 are in part front views and in part sections illustrating the arrangement, attachment, and operation of the weather-strip. Fig. 6 is a vertical transverse section showing the weather-strip raised or in the position it assumes when the door is open. Fig. 7 is a similar view showing the weather-strip in the position it assumes when the door is closed.

The weather-strip A is a sheet-metal plate and attached to a door B, adapted to swing in the usual way. The weather-strip is bent or curved upward at its upper edge to prevent a head wind driving rain over it and curved sharply inward at its lower edge *a*, so as to form a groove adapted to receive the free end of a wire spring C, as shown in Figs. 3, 6, 7. The other end *c* of the wire spring is secured to the door beneath the central portion of the weather-strip and projects outward in such manner as to hold the weather-strip lifted in the position illustrated in Fig. 6 when the door is open. The weather-strip is arranged beneath a molding or ledge *b*, which extends across the lower front portion of the door. The means of attachment are **U**-shaped staples *a'*, which, as shown in Figs. 3, 4, 5, are set in oblique position in the base of the molding *b*. The object of this arrangement of the staples is to cause the weather-strip A as it swings up and down thereon to move lengthwise slightly when the door is

opened and closed. In other words, when the weather-strip is being closed the end which is adjacent to the free edge of the door comes in contact with and rides underneath a stud or projection D, fixed in the adjacent jamb E, and is thus thrown down from the position indicated in Fig. 6 to that indicated in Figs. 1, 2, 5, 7.

In Fig. 6 the weather-strip is shown as just coming in contact with the stud D, and in Fig. 7 the door B has swung farther inward, so that the weather-strip has been pressed down upon the door-sill. In this operation the weather-strip is moved slightly endwise toward the jamb E. On the other hand, in opening the door a reverse movement of the weather-strip occurs, since as it rises from the position indicated in Fig. 6 it moves endwise away from the jamb E. It will be understood that while this movement is slight it suffices to facilitate the entrance of the weather-strip into the space between the jambs without its lower corner coming in contact with the jamb E, as would otherwise be the case. I am thus enabled to use a slightly longer weather-strip than would be otherwise practicable and to thereby form a closer fit or joint, so that rain is better excluded.

What I claim is—

1. The combination, with a swinging door and jambs between which it is adapted to fit, of a weather-strip attachment comprising a ledge or molding extending across the face of the door, the weather-strip proper consisting of a sheet-metal plate having its outer edge inturned and its upper edge outturned, **U**-shaped staples securing the weather-strip to the ledge, the same being set in an inclined position, and a spring secured to the door, its free end being engaged with the flange or lip formed on the front edge of the weather-strip, and a stop fixed in the jamb in position for engagement with the weather-strip as the door closes, whereby the latter is thrown downwardly and simultaneously moved lengthwise, substantially as described.

2. The combination, with a swinging door and a door-jamb provided with a stop, of a weather-strip attachment comprising the weather-strip proper formed of a metal plate having its outer edge inturned, staples pivotally securing the inner edge of the strip and arranged obliquely whereby to cause the weather-strip to move lengthwise as it swings up and down, and a spring attached to the

door and its free end engaging the ledge or flange of the weather-strip, substantially as described.

3. The combination with the swinging door and the jamb therefor provided with a stop, of a weather-strip and staples pivotally securing the inner edge of said strip and arranged obliquely whereby to give the strip a

slight lengthwise movement as the strip moves up and down, substantially as set forth.

THOMAS J. JOHNSON.
